a corporation of Massachusetts

Application June 30, 1949, Serial No. 102,274

8 Claims. (Cl. 49-2)

1

This invention relates to improvements in automatic machines for sealing filament mounts upon the ends of tubular lamp bulbs and relates particularly to automatic means for inverting the lamp bulbs after one end thereof has been sealed.

The mechanism includes a main carrier arm which is pivoted to swing substantially radially toward and from the circular turret of the sealing machine which contains a plurality of sealing heads. A lamp gripping and rotating head is mounted on the upper end of the main arm. Means are provided on this head to grip a lamp, remove it from the turret, invert it and replace it on the same sealing head from which it was removed, the inverting operation taking place while the main arm has been moved away from the turret and while the turret is indexing.

A driving means for the mechanism of the invention is connected to a driven member on the sealing machine and serves to accurately time the operations thereof to those of the inverter mechanism. A complete description will be set forth hereinafter.

It is an object of the invention to provide a mechanism of the type indicated which will function positively and without damage to the lamp bulbs which are inverted thereby.

A further object of the invention is to provide a mechanism for automatically inverting lamp bulbs in accurate timed sequence with the indexing of an automatic sealing machine associated therewith.

A further object of the invention is to provide a means for inverting the position of tubular lamps upon a lamp sealing machine without interfering with or interrupting the operation of the sealing machine.

A further object of the invention is to provide a mechanism which efficiently performs its end function with a minimum of operating parts.

A further object of the invention is to provide a mechanism for inverting tubular lamps after one end thereof has been sealed and in which the lamp bulbs are reversed and transposed by the same motion to a position opposite the head from which it was taken and after indexing of the head has taken place.

Other objects and features of the invention will more fully appear from the following description and will be particularly pointed out in the claims.

To provide a better understanding of the invention, a particular embodiment thereof will be now described and illustrated in the drawings in which:

2

Fig. 1 is a front elevation of the mechanism constituting the invention.

Fig. 2 is a side elevation of the mechanism shown in Fig. 1.

Fig. 3 is a cross section on line 3-3, Fig. 1, with the members shown in the actuated position.

Fig. 4 is a sectional view on line 4-4, Fig. 3, with the members shown in the actuated position.

Fig. 5 is a detail view showing the manner in which the ends of the operating cables of the mechanism are anchored to the operating drum.

The invention is described as applied to a machine for sealing the stem assembly end members of a tubular discharge lamp to the bulb portion thereof.

Such machines are equipped with a rotating turret or head member 1 upon which are peripherally arranged a plurality of sealing heads 2 of conventional design which employ gas heat to fuse the lamp elements to produce a gas tight envelope.

Suitable means are provided within the casing 3 for indexing the turret to present successive heads 2 to the various work stations between machine cycles.

The arm 6 has a cam follower 14 projecting therefrom which engages the cam 11. One or more springs 15 are secured to the arm 6 and to the frame 13 acting to hold the follower 14 upon the cam. The cam and follower are so arranged that the positive movement of the cam upon the follower moves the arm outward while the spring moves it inward. In this manner jamming of the arm against the machine is prevented in case a lamp or other object should accidentally come between the arm and a part of the machine.

To raise and lower the lamps at the required time the upper portion 9 of the arm 6 is moved by a lever 16 fulcrumed upon a fulcrum shaft 17 mounted on the frame 13. The lever 16 is disposed substantially horizontal and provided at its outer end with a connection 18. The connection 18 has top and bottom horizontal guides which embrace a follower roll 19 pivoted upon the upper section 9 of the arm 6.

By reason of the construction of the connection 18 movement of the lever 16 raises and lowers the portion 9 of the arm 6 but also permits free movement of the arm about its own pivot 7. The lever 16 has mounted thereon a follower roll 20 which is engaged by a cam 21 mounted on the cam shaft 12. The cam 21 has a major concentric portion which holds the arm portion 9 in

its top position throughout most of its cycle and a depressed portion acting to lower the lamp held in the gripping and inverting member 10 for a short period when the inverted lamp is re-delivered and another lamp is picked up.

Referring now to the details of the member 10 it has a shaft 22 rotatably mounted in a casing 23 which in turn is rigidly secured to the upper end of the arm 6. The shaft 22 is disposed radially to the turret 1 and has secured to its inner end a lampholder 24. The member 24 has a pair of lamp receiving grooves 25 which are parallel and spaced symmetrically from the shaft axis and separated by a distance equal to the pitch distance between the heads 2 upon the turret. A pair of spring pressed and slideable fingers 26 act with the grooves 25 to hold or release a lamp in a manner to be described.

The two fingers 26 are pressed against the lamps by springs 27 and are pivoted on a common pivot pin which is mounted in a transverse slide 28 which in turn is connected to an actuating pin 29 slideable in the body of the holder.

The member 24 has a circular indexing member 30 mounted on its shaft 22 which has a pair of notches 31 in the periphery thereof and spaced 180° apart. The member 30 may be a part of the hub of the member 24 as shown. A spring actuated detent arm 32 successively locks the member 24 at half revolution positions. Means are provided to rotate the member 24 when it is in its outer position away from the turret 1. A desirable means is shown wherein two sections of flexible steel cable 33 are wound upon and secured at their ends upon a drum 34 shown in Fig. 5. One section of the cable is connected to a take-up spring 35 while the other section is connected to an actuating rocker arm 36 pivoted near its midpoint and connected at its other end to a link 37 which in turn is connected to a lever 38 fulcrumed on the shaft 17. The lever has a follower roll 39 thereon which engages a cam 40 on the camshaft 12. The cam 40 is timed to pull down upon the cable through the various connections to rotate the member 24 one half turn while the arm 6 is in its outer position thus inverting a lamp held in the member 24.

It will be noted that in inverting the lamp it also becomes transposed the pitch distance between heads 2 so that the inverted lamp is in position to be replaced in the head from which it was removed, which head has in the meantime been indexed to its next succeeding position. Accurate 180° positions of the member 24 is maintained by the detent 32.

Coaction between the cam 40 and the vertical movement of the portion 9 of the arm is arranged not only to drive the drum 34 but to return the drum to its initial position after the lamp has been inverted. To do this a suitable ratchet and pawl mechanism 41 causes the drum 34 to drive the shaft 22 in one direction and to freely permit its return in the other direction.

If desired counterweighing means may be provided in connection with the vertical movement of the upper portion 9 of the arm 6.

The sealing machine includes separate sealing stations for each end of the lamp bulb 4. It is after the first sealing operation and just before the final sealing that the inverting mechanism 70 constituting the present invention functions.

In practice it is found desirable to first seal in the end containing the lamp exhaust tube although the principles of the invention apply independently of which end is first sealed. After

the first sealing operation the unfinished lamp is carried to a station at which an automatically operating arm grasps the lamp, raises it, removes it from the machine, inverts it, replaces and lowers it into sealing position.

This operating arm 6 is preferably of considerable length reaching down to a point near the machine supporting surface where it is pivoted at 7 to swing toward and from the machine in a plane substantially radial to the axis of the turret 1. The arm 6 is constructed to be inherently rigid, its upper portion being offset toward its operating position at the periphery of the turret. This offset is introduced to make room at the base of the machine for operating elements essential to the execution of other operations upon the lamp. However, the particular shape of the arm forms no part of the invention and is simply an expedient to overcome practical space design requirements.

The arm 6 is made in two parts, a main carrier or lower portion 8 pivoted at 7 and a second carrier or upper portion 9 mounted to slide vertically upon the rods 9X secured upon the portion 8.

25 The upper end of the upper portion 9 of the arm 6 has rotatably mounted therein a lamp gripping and inverting member 10 which is provided with means for swinging the lamps through 180° to prepare them for the second sealing operation.

30 To execute its required function the member 10 must be bodily manipulated which is done by movements of the arm 6. The member 10 is moved into position against the lamps in the machine and out again by swinging the arm 6 about its pivot 7. This movement is obtained by means of a cam 11 mounted upon a camshaft 12 rotatably mounted in a frame 13 connected to the base of the machine.

35 Means are provided for actuating the slide 28 for shifting the fingers 26. Any suitable means may be employed for this purpose. As shown herein, a lever 45, fulcrumed on shaft 101 supported by plates 102 attached to the casing 23, engages the end of the pin 29 (Fig. 4). One arm of a bellcrank lever 103 is mounted on shaft 101, the other arm of the bellcrank lever 103 having an end of link 46 connected thereto. The other end of link 46 is connected to an arm of bellcrank lever 104 which is mounted at 106 on the upper portion 9 of the arm 6. A link 105 connects the other arm of bellcrank lever 104 to lever 47 fulcrumed on the shaft 17.

40 The lever 47 has a cam face 48X thereon which is engaged by a roll 49 upon the end of an arm 49 fixed upon the camshaft 12. The arm 49 is positioned on the shaft 12 to cause actuation of the fingers 26 when the portion 9 of the arm 6 is at its low position as will appear more fully hereinafter.

45 The cam shaft 12 is driven to make one revolution during each indexing cycle of the turret 1. This may be done in any suitable manner. As shown the shaft 12 is driven from a shaft 50 which is one of the main drive shafts of the machine in general. Any suitable driving connection may be used such as the bevel gears 51 and a universal connection 51X.

50 The mechanism embodying the invention is so placed with respect to the sealing machine that the arm 6 will cause the member 24 to deliver an inverted lamp at the final sealing-in station where the unfinished lamp will be presented in accurate alignment to a stem assembly 53 upon the sealing head 2 after which heat is applied to

finish the lamp envelope which is then ready for the exhausting operation.

The operation of the mechanism is as follows. Let it be assumed first that the cam 11 has moved the arm 6 to its outer or retracted position at which time the member 24 is carrying a lamp in its left hand groove when looking toward the turret. While the arm is out the turret indexes in a counterclockwise direction and the cam 40 acts through its interconnecting elements to rotate the drum 34 which inverts the lamp and moves it over to a right hand position in the member 24.

The cam 11 then moves the arm 6 carrying the inverted lamp inward to the extended position where the lamp is above and in register with a lamp sealing machine head. This movement causes the lamp to enter the holding devices on the turret on the sealing head from which it was removed. The cam 21 now acts to lower the lamp to its sealing position and when the member 24 is at its lowest position the roll 48 and arm 49 engage the follower 48X on the lever 47 which acts through its system of links and levers 46 to push the pin 29 inward thereby releasing the delivered lamp and locking the adjacent uninverted lamp in the left hand groove of the member 24.

Continued movement of the cam 21 raises the uninverted lamp to clear its exhaust stem and lead wires by sliding it upward in its holders on the turret 1. The cam 11 now acts to swing the arm 6 back away from the turret carrying the uninverted lamp with it. The cam 40 then again acts to invert the lamp and thus complete the cycle.

What I claim is:

What we claim is:

1. In combination with a sealing machine for tubular lamps having a plurality of tube-carrying heads disposed about the periphery thereof, apparatus for successively inverting the position of the tubes thereon comprising: a main carrier located adjacent to the periphery of the sealing machine and moveable toward and from the tube-carrying heads disposed about the periphery thereof; a second carrier moveable vertically on said main carrier; a tube manipulator rotatably mounted on said second carrier and having tube gripping means thereon; means to move said main carrier inwardly toward the tube-carrying heads of the sealing machine to present said tube manipulator to said tubes and move it away therefrom; means to move said second carrier in a vertical plane; and means to rotate said manipulator to invert said tubes one at a time.

2. In combination with a sealing machine for tubular lamps having a plurality of tube-carrying heads disposed about the periphery thereof, apparatus for inverting the tubes carried by said heads comprising: a main carrier; means to move said carrier toward and from said tube-carrying heads; a second carrier moveable vertically on said main carrier; means for moving said second carrier in a vertical plane; a tube manipulator rotatably mounted on said second carrier; means on said tube manipulator for gripping and removing one tube and delivering a second tube during one in-and-out movement of said main carrier; and means for rotating said tube manipulator when said main carrier has been moved away from the tube-carrying heads to invert the tube held thereby.

3. In combination with an indexing sealing machine for tubular lamps having a plurality of tube-carrying heads disposed about the periphery

thereof, apparatus for inverting the tubes carried by said heads comprising: a tube manipulator, having two tube-receiving grooves therein spaced from one another the indexing pitch distance of the sealing machine, located adjacent to the periphery of the sealing machine; tube-gripping fingers on said tube manipulator coacting with the tube-receiving grooves therein to hold and release a tube; means for effecting oscillatory movement of said tube manipulator toward and from the tube-carrying heads of the sealing machine; means for effecting reciprocating movement in a vertical plane of said tube manipulator when it is located in the extended position; means for rotating said tube manipulator when it is located in the retracted position to invert the tube held thereby; and means for actuating said tube-gripping fingers to release an inverted tube to one of the tube-carrying heads and simultaneously grasp a tube from an adjacent tube-carrying head when the tube manipulator is in the extended position.

4. In combination with an indexing sealing machine for tubular lamps having a plurality of tube-carrying heads disposed about the periphery thereof, apparatus for inverting the tubes carried by said heads comprising: a carrier; means for effecting oscillatory movement of said carrier toward and away from the tube-carrying heads on the sealing machine; a tube manipulator, having a vertical axis, mounted on said carrier and having at least one tube-receiving groove therein spaced one-half of the sealing machine indexing pitch distance from the vertical axis of said tube manipulator; means on said tube manipulator for gripping a tube in the groove therein and releasing it therefrom when the carrier is in the extended position; means for effecting reciprocating movement of said tube manipulator in a vertical plane when the carrier is in the extended position; and means for rotating said tube manipulator 180° when the carrier is in the retracted position.

5. In combination with an indexing sealing machine for tubular lamps having a plurality of tube-carrying heads disposed about the periphery thereof, apparatus for inverting the tubes carried by said heads comprising: a main carrier; means for effecting oscillatory movement of said carrier toward and from said tube-carrying heads; a second carrier mounted on said main carrier; means for effecting reciprocating movement of said second carrier in a vertical plane when said main carrier is in the extended position; a tube manipulator rotatably mounted on said second carrier; means on said tube manipulator for gripping and releasing a tube; and means for rotating said tube manipulator to invert and transpose a tube therein the pitch distance of indexing movement of the sealing machine when the main carrier is in the retracted position.

6. In combination with an indexing sealing machine for tubular lamps having a plurality of tube-carrying heads disposed about the periphery thereof, apparatus for inverting the tubes carried by said heads comprising: a main carrier; means for effecting oscillatory movement of said carrier toward and from said tube-carrying heads; a second carrier mounted on said main carrier; means for effecting reciprocating movement of said second carrier in a vertical plane when said main carrier is in the extended position; a tube manipulator rotatably mounted on said second carrier and having a pair of parallel tube-receiving grooves therein spaced apart the pitch distance

of the sealing machine index, the vertical axis of said manipulator being half way between said grooves; means on said manipulator coacting with the tube-receiving grooves therein for gripping a tube in one of said grooves and releasing a tube from the other of said grooves when the main carrier is in the extended position; and means for rotating said tube manipulator when the main carrier is in the retracted position to invert a tube held in said manipulator.

7. In combination with a sealing machine for tubular lamps having a plurality of tube-carrying heads disposed about the periphery thereof, apparatus for inverting a tube on one of the tube-carrying heads comprising: a tube manipulator located adjacent to the periphery of the sealing machine; tube gripping means on said manipulator; means for effecting oscillatory movement of said tube manipulator toward and away from the tube-carrying heads on the sealing machine; means for effecting reciprocating movement in a vertical plane of said tube manipulator when it is in the extended position; means for rotating said tube manipulator when it is in the retracted position; and means for actuating said tube gripping means on said tube manipulator when the manipulator is in the extended position. 25

8. In combination with an indexing sealing machine for tubular lamps having a plurality of tube-carrying heads disposed about the periphery thereof, apparatus for inverting a tube on one of the tube carrying heads comprising: a tube manipulator located adjacent to the periphery of the sealing machine; a pair of tube gripping members on said manipulator and spaced from one another the indexing pitch distance of the sealing machine; means for effecting oscillatory movement of said tube manipulator toward and away from the tube-carrying heads on the sealing machine; means for effecting reciprocating movement in a vertical plane of said tube manipulator when it is in the extended position; means for rotating said tube manipulator when it is in the retracted position; and means for actuating the pair of tube gripping members on said manipulator when the manipulator is in the extended position to simultaneously grasp a tube in one of the tube gripping members and release a tube from the other tube gripping member.
